UNITED STATES PATENT OFFICE

2,269,925

VENDING BOOTH

Albert Wnętrzak, Cicero, Ill., assignor of two-fifths to Anthony F. Krasniewski, Cicero, Ill.

Application June 17, 1940, Serial No. 340,950

6 Claims. (Cl. 20—2)

The present invention relates to vending booths and has for its main object the provision of a booth including a pair of foldable doors and so arranged as to be capable of being converted into a supplementary housing constituting a protection for the vendor against inclement weather.

A still further object of the present invention is the provision of a vending booth having a shiftable platform, which in conjunction with a foldable door may constitute a supplementary housing as protection for a vendor against inclement weather.

A still further object of the present invention is to generally improve the construction of a vending booth.

With the above general objects in view and others that will appear as the invention is better understood, the same consists in the novel construction, combination and arrangement of parts hereinafter more fully described, illustrated in the accompanying drawings and pointed out in the appended claims.

In the drawings forming a part of this application, and in which like designating characters refer to corresponding parts throughout the several views:

Fig. 1 is a front elevational view of the present invention;

Fig. 2 is a cross-sectional view on horizontal plane, on line 2—2 of Fig. 1;

Fig. 3 is a fragmentary vertical cross-sectional view on line 3—3 of Fig. 1; and

Fig. 4 is a side elevational view of the booth.

Referring in detail to the present drawings there is shown therein a vending booth having floor 10, a pair of side walls 11 and a rear wall 12.

The booth further includes a horizontal partition wall 13 disposed above floor 10, and which is positioned within braces 14, the latter affixed adjacent the front ends of side walls 11. The device further includes a pair of side panels 15 rigidly affixed to floor 10, partition wall 13 and braces 14. Said floor 10, rear wall 12, partition wall 13 and panels 15 define a storage housing to which access may be had through door 16 positioned within the pair of panels 15. Said partition wall 13 also constitutes a counter upon which the goods may be displayed.

Corner pieces 17 positioned within corners defined by side walls 11 and rear wall 12 strengthen the construction of the booth.

Disposed above said horizontal partition wall 13 and within the rear ends of side walls 11 is shelf 18 resting upon horizontal bars 19, the lat-

ter affixed to said side walls 11. Said shelf 18 constitutes additional space upon which goods may be placed.

Positioned below floor 10 is a pair of sliding platforms 20, each of which is guided by a pair of rails 21, affixed to the underface of floor 10, and further held in position by a cross piece 22, the latter held within side walls 11. Metallic runners 21' may be affixed to the underface of each platform 20 for facilitating the sliding movement thereof within said rails 21.

Each of said platforms 20 is adapted for longitudinal sliding movement into or out of the vending booth, and a suitable mechanism for outwardly sliding each of said platforms 20 is provided and consists of a cord 23, one end of which is affixed to said platform 20 as at 24 and adjacent the rear end of said platform and in front of recess 25. Affixed to cross piece 22 and extending rearwardly thereof is a pulley 26 over which said cord 23 passes and extends rearwardly therefrom to pulley 27 which is affixed to rear wall 12, adjacent the lower end thereof and below floor 10. From there through openings 28 made in floor 10, partition wall 13 and shelf 18, said cord 23 is extended above shelf 18 and passes through pulley 29 positioned and rigidly affixed on shelf 18 and adjacent its opening 28.

From the description of the mechanism for the purpose of extending or outwardly shifting platform 20 it will be apparent that upon exerting manual pull upon the free end of cord 23 platform 20 will be outwardly shifted substantially to the position illustrated in Figs. 2 and 3. Whenever it is desirable to retract platform 20 to its inoperative position shown in Fig. 1, the same is manually pushed until the same rests completely below floor 10. When in that retracted inoperative position of platform 20, pulley 27 will remain within recess 25, the latter providing a clearance space for said pulley so that the remaining rearward edge of said platform 20 may contact with the rear wall 12.

The vending booth further includes a double door, each made of a pair of folding panels 30, the doors being suspended upon hinges 31 affixed to the front ends of side walls 11. Each pair of panels 30 in each door are connected by hinges 32.

Whenever it is found to be desirable to provide a supplementary housing for protecting the vendor against inclement weather, first both doors are shifted to an open position, thereupon platforms 20 are extended by operating cord 23 as aforesaid so as to bring one or both of said

platforms 20 to the position shown by dotted lines in Fig. 2. Thereupon the door is shifted so that the outer panels 30 thereof would remain in parallel relation with the outer edge of platform 20, as seen by dotted lines in Fig. 2, and thereupon the inner panels 30 of the door are folded until the inner faces of said inner panels 30 of the door contact with the outer edge of platform 20, the position shown by dotted lines in Fig. 2 and by full lines in Fig. 3. To engage the inner panel 30 of the door with its co-operating platform 20 so as to maintain the door in a rigid operative engagement with platform 20, a hook 33 upon the inner panel 30 of the door may be provided.

The vending booth is further provided with a pair of cleats 34 affixed to side walls 11 and adjacent the front edges thereof and with a pair of like cleats 35 adjacent the rear edges of said walls 11. Similar cleats 36, and under roof 31 are provided to define a rectangular area upon each of said side walls 11 and for which said cleats 34, 35 and 36 constitute a frame, and within which space one door 30—30 may be placed when removed from hinges 31 and suspended upon like hinges 38 mounted upon cleats 35. Said doors 30—30 may be so removed from their normal hinges 31 and placed upon their respective side walls 11 and within cleats 34, 35 and 36 whenever fair weather permits the front of the booth to be entirely open, as is shown in Fig. 1. Fasteners 39 upon cleats 34 will further hold doors 30—30 in position upon side walls 11.

Roof 31 may extend forwardly to form an overhanging eaves remaining over platforms 20 when the same are in an extended operative position to constitute a further protection from above.

Affixed to one brace 14 is a bearing 40 for maintaining in a pivotal adjustment a bracket arm 41, the latter supporting seat 42 which may be extended outwardly from behind the adjacent panel 15, as is shown in dotted lines in Fig. 2 and in full lines in Fig. 3. Recess 43, made in the upper edge of panel 15 permits unobstructed movement of said seat 42 from operative or inoperative position. When said seat 42 is not in use the same may be shifted into an inoperative position and within the housing below partition wall 13, as is seen in Fig. 2. At the opposite side of the booth a slidable bench 44 positioned below partition wall 13 may be provided with recess 45 made in the upper edge of the adjacent panel 15 permitting unobstructing movement of said bench 44 into operative or inoperative position.

While there is described herein a preferred embodiment of the present invention, it is nevertheless to be understood that minor changes may be made therein without departing from the spirit and scope of the invention as claimed.

What I claim as new is:

1. In a structure, including a floor and at least three vertical walls extending therefrom to form a main housing, a platform disposed adjacent said floor and adapted to be shifted into an operative or inoperative position, and a folding door in pivotal relation with one of said vertical walls of said main housing, the panels of said folding door being adapted to assume substantially parallel contacting positions with respect to two adjacent angularly related edges of said platform when the same is in an extended operative position to form in co-operation therewith a supplementary housing.

2. In a structure, including a floor and at least

three vertical walls extending therefrom to form a main housing, a platform disposed adjacent said floor and adapted to be shifted into an operative or inoperative position, and a folding door in pivotal relation with one of said vertical walls of said main housing, said door having a plurality of folding panels, said panels being adapted to assume angular contacting relative position corresponding to the angular edges of said platform when the latter remains in an extended operative position for forming in co-operation with said platform a supplementary housing.

3. In a structure including a plurality of vertical walls and a floor constituting a main housing, a platform disposed adjacent said floor for outer shifting movement, and a door in a pivotal relation with one of said vertical walls of said main housing, said door consisting of a pair of folding panels, said door when in a closed relation with said main housing being in a transverse relation with said platform and constituting a closure for said main housing, said platform being adapted for outer shifting movement when said door remains in an open position with relation to said main housing, said panels being adapted to assume a substantially contacting and coextensive position with a pair of intersecting edges of said platform when the latter remains in an outwardly extended position for providing a housing supplementary to said main housing.

4. In a structure including a plurality of vertical walls and a floor constituting a main housing, a platform disposed adjacent said floor for outer shifting movement, a door in a pivotal relation with one of said vertical walls of said main housing, said door consisting of a pair of folding panels, said door when in a closed relation with said main housing being in a transverse relation with said platform and constituting a closure for said main housing, said platform being adapted for outer shifting movement when said door remains in an open position with relation to said main housing, said panels being adapted to assume a substantially contacting and coextensive position with a pair of intersecting edges of said platform when the latter remains in an outwardly extended position for providing a housing supplementary to said main housing, and means for rigidly engaging said panels with said platform when the latter remains in an outwardly extended position.

5. In a structure, a floor and side walls constituting a main housing, a platform disposed adjacent said floor for outer shifting movement, and a door in a pivotal relation with one of said side walls, said door consisting of a pair of folding panels, said door when in a closed relation with said structure being in a transverse relation to the path of movement of said platform and constituting a closure for said main housing, said platform being adapted for outer shifting movement from said floor when said door remains in an open position with relation to said main housing, said panels being adapted to assume a substantially contacting and coextensive position with a pair of intersecting edges of said platform when the latter remains in an outwardly extended position for providing a housing supplementary to said main housing.

6. In a structure, a main housing comprising a floor and vertical rear and side walls, a platform disposed adjacent said floor for outer shifting movement, and a door including a pair of folding panels, one of said panels being in a vertical pivotal relation with one of said side walls

and at a forward edge thereof, said door when in a closed relation with said structure being by its lower marginal edge in a transverse relation to the path of movement of said platform and providing a closure for said main housing, said platform being adapted for outer shifting movement from said floor when said door remains in an open position with relation to said main housing, the panel of said door nearest to said one of said side walls being adapted to contact with the side marginal edge of said platform

when the latter is in an extended position, and the remaining panel being adapted to assume an angular position with respect to the first panel for contacting with the adjacent angular front marginal edge of said platform when the latter remains in an extended position, said panels when in contactual position with said platform when the latter is in an extended position providing in co-operation with said platform a housing supplementary to said main housing.

ALBERT WNETRZAK.
